BALE TIE PACKAGE

Harry W. Hill, Sterling, Ill., assignor to North-
western Steel and Wire Company, a corpora-
tion of Illinois

Application March 14, 1934, Serial No. 715,418

7 Claims. (Cl. 206—46)

This invention has to do with bundles or packages of lengths of wire or the like for shipping purposes.

In the past, it has been common to arrange a plurality of lengths of wire such as bale ties together in the form of a bundle and to apply entirely by hand anchor rings of wire at spaced points along the bundle, bringing the ends of each ring together and twisting the same and then bending the parts thus twisted flat against the bundle. In this manner, the bale ties and the like were kept together and separation was prevented during shipping and handling of the bundle as a whole. However, this form of packaging is undesirable for the reason that the anchor rings slip along the bundle and thus require rearrangement, and for the further reason that when the rings are cut off by the user of the ties or the like, frequently one or more of the rings will find their way into the material baled, such as cotton, hay and the like, in such a manner as to defy detection.

It is an object of the invention to provide a bundle or package of the character referred to, including a primary wrapping element arranged in spiral fashion lengthwise of the bundle, so as to properly bind the bundle throughout the entire length thereof and to provide a single piece which, when the bundle is unwrapped, may be removed as a unit.

It is a further object of the invention to provide a wire package including wrapping means arranged to securely bind the bundle and to be removed as a unit therefrom.

Another object of the invention resides in the provision of a wrapping for a bundle of wire or the like, the wrapping being of such construction as to provide substantially continuous engagement with the bundle of wire substantially throughout the length of the bundle.

A further object resides in the provision of a package presenting substantially no sharp projections, thereby making for ease and safety in handling and eliminating injury to adjacent packages or other articles.

Further objects and advantages of the invention will appear as the description proceeds.

This invention (in preferred forms) is illustrated in the drawing and hereinafter more fully described.

On the drawing:

Figure 1 is an elevational view, partly broken away, showing an unwrapped bundle of baling wire, with the cap at the head of the bundle

partly withdrawn to show how the wires at that end are preliminarily secured together.

Figure 2 is a view similar to Figure 1, but showing the bundle after the final wrapping operation has been completed in accordance with this invention.

Figure 3 is a fragmentary elevational view showing the tail end of the bundle after the bundle is completely wrapped in accordance with this invention.

As shown in the drawing:

In the practice of my invention, a plurality of wire elements such as bale ties are "bunched" or placed together and preliminarily secured as by wire rings preferably adjacent the ends thereof. One arrangement for this purpose is shown in Figure 1, wherein the ties to be bundled are designated by the reference character 1, preliminarily anchored at their head ends at 2 as by a ring and at the tail end thereof by a ring 3. A burlap or like flexible covering 4 is then placed over the head end of the assembly of ties 1 as shown in Figure 1, and anchored thereon by the rings 5 and 9. Another anchor ring 6 is placed about the ties adjacent the free end of the covering 4, one end 7 of the strand to be employed in wrapping the bundle in accordance with this invention being anchored to the ring 6 as shown in Figure 2. This strand 8 is extended from its end 7 along the cover 4 toward the end at the head of the bundle and looped around the end of the same and returned to a point in the vicinity of its end 7.

The wrapping strand 8 is then spiraled around the bundle toward the tail end thereof as shown in Fig. 2 and at the tail end of said bundle said strand 8 is wound in closely contacting coils against the tail end of the bundle to provide an enclosing coiled cap 10 for the tail end thereof as shown in Fig. 2. After the protecting cap 10 has been formed over the tail end of the bundle, the strand 8 is sheared off.

In describing the present invention, the bundle chosen to illustrate the package is merely exemplary, since a bundle of any sort of wire or other material may be wrapped by the same means. The wire constituting the bundle herein disclosed is of the character employed in tying bales of hay, waste paper and the like, and comprises an end portion which is bent upon itself to form an eye, the contacting portions being thereupon twisted about each other to resist separation. The eye thus constitutes a loop through which the other end of the wire may be passed during the process of tying the bale.

When the wrapping operation involving the strand 8 is completed, a suitable preferably flexible covering 11 of burlap or the like is placed over the tail end of the bundle as shown in Figure 3, said covering being tied in place by any suitable means such as anchor rings 12.

It is to be appreciated that the head end of the spiral wrapping strand may be secured to the head end of the bundle in any suitable manner other than that specifically described, and from the point of securement the stand may be spiral wrapped to the bundle in the manner above described, the opposite or tail end being secured likewise as described.

The wrapping strand may, for ornamental purposes, be copper or otherwise plated to lend a pleasing and distinctive appearance to the bundle. The wrapping strand and other wrapping elements are preferably sufficiently strong to resist injury to themselves and the bundle, resulting from handling and shipping of the bundles.

The term "bundle" in the description and claims is to be understood as including in its scope an assembly of elongated pieces and also a length of elongated material.

I am aware that many changes may be made, and numerous details of construction may be varied, through a wide range, without departing from the principles of this invention, and I, therefore, do not purpose limiting the patent granted hereon, otherwise than necessitated by the prior art.

I claim as my invention:

1. A package including an assembly of lengths of wires or the like with free ends, and protective means for said ends, said means comprising a peripheral wall of closely wound coiled wire formed to surround the lengths at the ends thereof and an end wall extending inwardly from and in substantially coaxial relation to said peripheral wall so as to cover those free ends of the lengths adjacent said peripheral wall.

2. A package comprising a bundle of lengths of wire or the like, a cover of yieldable material on one end of the bundle, a wrapping strand secured adjacent said end and wrapped longitudinally about said cover, means embracing the strand thus wrapped and the cover, the wrapping strand beyond said means being wound in an attenuated spiral lengthwise about the body of the bundle, and in relatively closely related coils about and beyond the other end of the bundle and extending toward the axis of the bundle to

protect the corresponding ends of said lengths, a cover of yieldable material over the protecting portion of the wrapping strand, and means for securing the last mentioned cover in place.

3. A package comprising a bundle of lengths of wire or the like, a cover of yieldable material on one end of the bundle, a wrapping strand secured adjacent the said end and wrapped longitudinally about said cover, means embracing the cover, the wrapping strand beyond said means being wound in an attenuated spiral lengthwise about the body of the bundle, and in relatively closely related coils about and beyond the other end of the bundle and extending toward the axis of the bundle to protect the corresponding ends of said lengths, a cover of yieldable material over the protecting portion of the wrapping strand, and means for securing the last mentioned cover in place.

4. A package comprising a bundle of lengths of wire or the like, a cover of yieldable material on one end of the bundle, a wrapping strand secured adjacent the said end and wrapped longitudinally about said cover, the wrapping strand beyond said cover being wound in an attenuated spiral lengthwise about the body of the bundle, and in relatively closely related coils about and beyond the other end of the bundle and extending toward the axis of the bundle to protect the corresponding ends of said lengths, a cover of yieldable material over the protecting portion of the wrapping strand, and means for securing the last mentioned cover in place.

5. A package comprising a bundle of elongated elements, and a wire wrapped around said bundle and forming a coiled cap over one end of said bundle.

6. A package comprising a plurality of elongated elements, a wire anchored at one end to said bundle and spirally coiled around said bundle and closely coiled over one end of said bundle to form an end cap therefor.

7. A package comprising a bundle of elongated elements, a cover of yieldable material on one end of said bundle, a wrapping strand secured adjacent the inner end of said cover and wrapped longitudinally about said cover, the wrapping strand beyond said cover being spirally wound around said bundle toward the opposite end and having a series of closely wound coils forming an end cap for said bundle.

HARRY W. HILL.
